Lorris Vester Hagewood, Gatlinburg, Tenn.

Application April 15, 1952, Serial No. 19,333

Term of patent 14 years

(Cl. D87--3)

To all whom it may concern:

Be it known that I, Lorris Vester Hagewood, a citizen of the United States of America, residing at Gatlinburg, in the county of Sevier and State of Tennessee, have invented a new, original, and ornamental Design for a Handbag, of which the following is a specification, reference being had to the accompanying drawing, forming part thereof, and wherein:

Fig. 1 is a front elevation of a handbag, in closed position, embodying my new design.

Fig. 2 is a top plan view of the handbag shown in Fig. 1, in open position.

Fig. 3 is an end view of the handbag shown in Fig. 1.

Fig. 4 is a fragmentary bottom plan view of the handbag shown in Fig. 1.

The back and end not shown are the same, respectively, as the front and end shown.

Characteristic features of my design reside in the horizontal strip construction of the bag, in combination with a looped type drawstring. The back and end not shown are the same respectively as the front and end shown.

I claim:

The ornamental design for a handbag, substantially as shown and described.
